(57) **CLAIM**

The ornamental design for an aerosol delivery device cartridge, as shown and described.

DESCRIPTION

FIG. 1 is a bottom perspective view of the aerosol delivery device cartridge showing the new design;

FIG. 2 is a top perspective view of the aerosol delivery device cartridge;

FIG. 3 is another top perspective view of the aerosol delivery device cartridge;

FIG. 4 is a front elevational view of the aerosol delivery device cartridge;

FIG. 5 is a rear elevational view of the aerosol delivery device cartridge;

FIG. 6 is an elevational view of a side of the aerosol delivery device cartridge;

FIG. 7 is an elevational view of the opposing side of the aerosol delivery device cartridge;

FIG. 8 is a top plan view of the aerosol delivery device cartridge; and,

FIG. 9 is a bottom plan view of the aerosol delivery device cartridge.

The broken lines shown in the drawings depict portions of the aerosol delivery device cartridge that form no part of the claimed design.
